RUBBER HEEL

Donald M. Welch, Winchester, Va., assignor to
O'Sullivan Rubber Company, Inc., Winchester,
Va., a corporation of Delaware

Application December 22, 1942, Serial No. 469,833

2 Claims. (Cl. 36—59)

This invention relates to rubber heel construction and more particularly to a structure having a resilient body portion and an integral wearing portion which may be of somewhat less resilient material but which has greater resistance to abrasion than the material of the body portion.

The portions of a rubber heel which are subjected to the greatest wear are those adjacent the rear edge of the heel and adjacent the side edges near the back of the heel. Rubber compositions having sufficient resiliency to produce the desired cushioning effect for rubber heels are, in general, not sufficiently resistant to abrasion to provide long wearing qualities unless made of high quality expensive rubber compositions and, even if such high quality materials are employed for the body of the heel, improved heel life can be obtained by employing a more highly wear resistant material for the portions subjected to greatest wear.

In accordance with the present invention a rubber heel having a highly resilient body portion is provided with an integrally bonded wearing portion having high resistance to abrasion. The wearing portion also preferably has sufficient resiliency to provide some cushioning effect and is supported on part of the body of more resilient material so as to produce a longer wearing rubber heel having all of the desirable properties of conventional rubber heels made throughout of resilient rubber. By such structure the body of the heel can be made of less expensive rubber or rubber-like material having relatively low resistance to abrasion so long as it has the requisite resiliency.

It is therefore an object of the invention to provide an improved rubber heel construction in which a material having high resistance to abrasion but relatively low resiliency is integrally combined with a resilient body portion to produce a longer wearing rubber heel.

Another object of the invention is to provide an improved rubber heel construction in which a body portion of high resiliency but low resistance to abrasion is protected from wear by a wear resistant portion cushioned upon the resilient material of the body portion.

A further object of the invention is to provide a resilient rubber heel with a less resilient wearing portion of rubber which contains fibers or cords oriented to provide improved wearing qualities while still retaining substantial cushioning properties.

Other objects and advantages of the invention will appear in the following description of pre-

ferred embodiments of the invention given in conjunction with the attached drawing, of which

Fig. 1 is a horizontal cross-section through a heel structure in accordance with the present invention and taken on the line 1—1 of Fig. 2;

Fig. 2 is a vertical section taken on the line 2—2 of Fig. 1;

Fig. 3 is a fragmentary bottom view of the heel of Figs. 1 and 2 showing the position of the projecting wearing portion;

Fig. 4 is a bottom view partly in section along the line 4—4 of Fig. 5 of a modified heel structure; and

Fig. 5 is a vertical section taken on the line 5—5 of Fig. 4.

Referring particularly to Figs. 1 to 3 of the drawing the heel shown therein is provided with a body portion 10 of resilient material such as properly compounded vulcanized rubber and a wearing portion 11. The wearing portion preferably comprises fibers bonded together with a continuous phase of vulcanized rubber so as to provide a long wearing material having substantial cushioning effect or resiliency. As shown in Figs. 2 and 3 the wearing portion 11 preferably has a portion 12 extending downwardly below the plane of the lower surface of the heel so that the wearing portion of the heel may be subjected to substantial wear before the lower surface of the body portion of the heel becomes subjected to excessive abrasion. As shown in Figs. 1 and 3, the wear resistant portion of the heel preferably extends across the back of the heel and forwardly along the sides for a major portion of the length of the heel and as shown in Fig. 2 the wear resistant portion 11 preferably comprises a part only of the thickness of the heel so as to be cushioned by a portion 13 of the more resilient material of the body 10 extending between the wear resistant portion 11 and the upper surface of the heel. The structure of Figs. 1 to 3 may also be constructed with a recess 14 adjacent the upper surface thereof having a central supporting column 15 to provide for greater resiliency and also to save unnecessary material. The heel structure may also have the usual nailing holes 16 and metal washers 17 or any other suitable or conventional structure or method for attaching the heel to a shoe may be employed and the heel may have any desired ornamental design 18 impressed upon its lower surface.

The modified heel structure shown in Figs. 4 and 5 is essentially similar to that shown in Figs. 1 to 3 except for the size and shape of the wear resistant portion 19. This structure may also

have a resilient body portion 20 having a part 21 extending between the wear resistant portion 19 and the upper surface of the heel. The wear resistant portion 19 preferably occupies approximately the rear one half of the lower surface of the heel and is provided with an intermediate portion 22 extending downwardly below the plane of the lower surface of the heel. The heel shown in Figs. 4 and 5 may also be provided with a cushioning recess 23 having a supporting column 24 as well as the usual nail holes 25 and metal washers 26. As in the case of the heel shown in Figs. 1 to 3, any suitable ornamental design 27 may be impressed upon the lower surface of the heel.

The preferred material making up the wear resistant portion of the heel is a vulcanized rubber containing a substantial amount of cords or fibers oriented so as to extend generally vertically of the heel. A particularly suitable material is that obtained from reclaiming tire carcasses or similar material containing cords or fabric. In obtaining suitable material from tire carcasses the whole carcasses are shredded and then softened and plasticized by known reclaiming and devulcanizing agents to produce a plastic mass which is sheeted upon a rubber mill or calendar. Care is taken that the cords or fibers are only partly disintegrated so that a substantial amount of fibers remain therein and are oriented longitudinally of the sheet during the sheeting operation. A plurality of the sheets are then superposed and the resultant multi-ply structure compressed and sheared transversely of the sheets and fibers therein to produce members of vulcanizable stock having the fibers oriented perpendicularly to the sheared surfaces.

While the reclaiming of tire carcasses or similar material above described is a particularly good source of inexpensive relatively high quality reinforced rubber for fabricating the wear resistant portion of the heel, it will be apparent that similar materials may be produced by admixing cords or fibers with properly compounded virgin rubber, reclaimed rubber or rubber-like material such as so-called synthetic rubber. Such materials may be milled and sheeted so as to orient the fibers in the same manner as is the material reclaimed from tire carcasses. It has been found that structures in which the cords or fibers extend generally vertically of the heel produce the best wearing qualities combined with a substantial cushioning effect. It will be further apparent, however, that structures in which the cords or fibers are oriented in a horizontal plane or even structures which have no general orientation of the fibers may be employed with somewhat lesser efficiency. In any case the cords or fibers somewhat stiffen the vulcanized material and increase its resistance to abrasion while at the same time providing a rubber-like surface for the wearing portion of the heel which has greater cushioning properties than such materials as leather, wood or metal.

The body portion of the heel may be of any suitable rubber or rubber-like resilient material since it is not, in normal use, subjected to excessive wear. It has been found that even relatively low quality inexpensive reclaimed rubber may be employed, as such material may be com-

pounded to give excellent resiliency even though its wearing qualities are not adequate for the wearing portion of the heel. Thus the entire heel of the present invention may have excellent cushioning and wearing properties although made throughout of relatively inexpensive materials. It is of course possible to employ higher quality material for the body portion of the heel, such as virgin rubber or high quality synthetic rubbers. Also the material having greater resistance to wear may extend throughout the thickness of the heel in cases where less resiliency is required.

In making the heel of the present invention, it is preferred to form the same in a single molding operation by correctly positioning both the material of the body portion of the heel and of the wearing portion in the mold at the same time and simultaneously curing both portions of the heel with heat and pressure. By this operation the wearing portion of the heel is integrally bonded to the body portion to produce an integral rubber heel having portions of different characteristics so as to provide a long wearing heel constructed of relatively inexpensive materials.

The term "rubber" as employed in the claims is intended to be inclusive of natural virgin rubber, reclaimed rubber and rubber-like materials such as so-called synthetic rubbers, for example buna S, buna N, Thiocols, neoprene, etc., having physical properties similar to those of rubber.

While I have disclosed the preferred embodiments of my invention, it is understood that the details thereof may be varied within the scope of the following claims:

I claim:

1. As an article of manufacture, a rubber heel having a body portion of resilient vulcanized rubber and a wearing portion of abrasion resistant material containing vulcanized rubber, said wearing portion comprising vulcanized rubber containing textile fibers substantially all oriented so as to extend generally vertically of said heel and being positioned adjacent the rear and rear side edges of the heel, said wearing portion being integrally bonded to said body portion and extending downwardly below the plane of the lower surface of the body portion of the heel to provide a wearing surface which protects the lower surface body portion of the heel from excessive abrasion and extending a part only of the distance from the bottom surface of the heel so as to be cushioned by a portion of the resilient rubber of the body portion of the heel.

2. As an article of manufacture, a rubber heel comprising a body portion of reclaimed rubber having relatively high resiliency but low resistance to abrasion and an integrally bonded wearing portion positioned adjacent the rear of the heel and composed of reclaimed rubber containing fibers oriented so as to substantially all extend substantially vertically of the heel, said wearing portion having an extension providing a wearing surface positioned below the plane of the lower surface of the body portion of the heel and occupying approximately half the thickness of said heel so as to be cushioned by the resilient material of said body portion.

DONALD M. WELCH.
